UNITED STATES PATENT OFFICE.

EMIL EISENKRAFT, OF BROOKLYN, NEW YORK, ASSIGNOR TO A. SCHRADER'S SON, INCORPORATED, OF BROOKLYN, NEW YORK, A CORPORATION OF NEW YORK.

PAPER BOX OR CARTON.

1,370,525.

Specification of Letters Patent.

Patented Mar. 8, 1921.

Application filed September 22, 1915. Serial No. 52,000.

To all whom it may concern:

Be it known that I, EMIL EISENKRAFT, a subject of the Emperor of Germany, residing in the borough of Brooklyn, county of 5 Kings, city and State of New York, have invented certain new and useful Improvements in Paper Boxes or Cartons, of which the following is a specification.

This invention relates to the construction 10 of paper or card-board boxes or cartons especially constructed and adapted for containing small oblong articles for storage and shipment.

The box is made of stiff paper or card- 15 board cut and folded in such way as to form the bottom, sides and ends of the box, with an inner portion in the nature of a false bottom which is shaped to fit the article to be inclosed so as to hold it in place, all 20 being preferably so constructed that the box will retain its shape without the necessity of using paste.

Accordingly the invention provides a paper box having flaps joined to form the 25 sides and ends, and having an inner flap or portion partially filling the box and partly cut away or otherwise conformed to engage the article to be inclosed in the box. The box preferably has a cover adapted to slip 30 over it and constructed in similar manner.

The accompanying drawings show several different embodiments of the invention.

Figure 1 is a perspective view of a box or carton of one construction;

Fig. 2 is a plan of the blank from which 35 this box is made;

Fig. 3 is a longitudinal section through the box;

Fig. 4 is a transverse section;

Fig. 5 is a transverse section through the end on the line 5—5 in Fig. 3;

Fig. 6 is a section corresponding to Fig. 3 showing a modified construction;

Fig. 7 is a cross-section corresponding to 45 Fig. 4 showing a modified construction;

Fig. 8 is a longitudinal section, and Fig. 9 is a plan showing a further modified construction;

Figs. 10 and 11 are longitudinal sections 50 showing two other modified constructions;

Fig. 12 is a perspective view showing a suitable cover for the carton shown in any of the preceding figures;

Fig. 13 is a longitudinal mid-section 55 through the cover;

Figs. 14, 15 and 16 show another modified construction of carton, Fig. 14 being a longitudinal horizontal section on the line 14—14 in Fig. 16, which is a transverse section, and Fig. 15 is a longitudinal mid-section;

Fig. 17 is a sectional perspective showing a multiple carton, that is, one for holding a series of articles;

Fig. 18 is a longitudinal section corresponding to Fig. 3 and showing a further modified construction;

Fig. 19 is a transverse section of Fig. 18;

Fig. 20 is a plan of the blank from which the box shown in Figs. 18 and 19 is made;

Fig. 21 is a longitudinal section of the box;

Fig. 22 is a plan of a blank from which the box shown in Figs. 23, 24 and 25 is formed;

Fig. 23 is a transverse section of the box, Fig. 24 a longitudinal mid-section, and Fig. 25 a plan.

The box shown in Fig. 1 is made from the blank A shown in Fig. 2. This is a blank 80 of suitably stiff paper or card-board cut to the shape shown and bent along the dotted lines so as to form a box bottom a, sides b b, ends c c, end flaps b' b', side flaps b² b², and end tucks c¹ c². The blank also has a false bottom piece which as a whole is lettered B, which in Fig. 2 is constructed as a tongue integral with one of the end tucks c' and comprising sections d d near one end intersected by a hole e and sections d' d' near 90 the other end and intersected by a hole e', while between them is a section f.

To form the box shown in Fig. 1, the blank shown in Fig. 2 first has its side flaps b² turned in and down upon the side sections b b, being preferably pasted down. The end flaps b' are turned up at right angles, and the sides b are then turned up at right angles, which brings the end flaps b' on opposite sides together so that they partially 100 overlap at the ends of the box. Then the ends c c are bent up at right angles so that they lie against the outer faces of the end flaps. Then the end flaps c' c' are bent around the flaps b' and turned down inside 105 the ends of the box. This brings the end flap c² down upon the bottom of the box as shown in Fig. 3. The tongue B is then laid down within the bottom of the box, its sections d d' being creased or partially folded on the 110

dotted lines so that these sections form respectively humps g g projecting up within the box, as shown in Fig. 3, the extreme end being held in the angle at one end as shown 5 in Fig. 3, and the middle part of the tongue being preferably fastened to the bottom by paste or gum. The holes e e' now form sockets, as best shown in Figs. 1 and 4, for receiving the article to be inclosed. In Fig. 10 10 the inclosed article is shown by the dotted circle x , and in Fig. 3 it is shown by the dotted line x . Of course the article thus indicated in dotted lines is given only by way of illustration, as the box or carton may be 15 internally shaped to conform to an article of any conformation desired.

In the construction of box thus described it will be understood that the end flaps or ears b' are confined between the end walls 20 and flaps c c' , whereby the sides and ends are held in their proper relations, and the inner end flaps c' are held in place either by paste or by the stiffness of the false bottom section or tongue B; the humps g of which 25 tending to straighten it, give the tongue a tendency to elongate, whereby the outer sides of these humps press toward the opposite bottom end corners of the box and thus hold the flaps c' in place. The humps g g abut 30 at their ends against the side flaps b^2 , so that if these are not pasted down to the sides b the humps serve to hold them in place. Thus the entire carton may be made without 35 the use of any paste, so that the cartons may be shaped flat and quickly folded into box shape when desired for use.

The modification shown in Fig. 6 differs from that already described in having three humps, the middle hump g' being added. 40 Otherwise the construction is the same as already described.

In the construction shown in cross-section in Fig. 7, the side flaps b^2 are made of greater width than in the construction first 45 described, so that they have an extra portion or tongue b^3 and this is folded down horizontally on the flat portion f of the tongue or false bottom B, being preferably pasted down in order to hold the said tongues in 50 place in the stretch between the humps.

In the construction shown in Figs. 8 and 9 the inner lining or false bottom instead of being made of one tongue formed at one end of the blank as shown in Fig. 2, is made of 55 two tongues B' and B² projecting from the opposite ends of the blank and meeting on a line h in the middle. Each of these tongues is bent to form one hump g with its hole e , and to form one bottom flap f' to lie on the 60 box bottom, being preferably pasted down. In other respects the construction is the same as that first described.

Fig. 10 shows a construction like that first described except that the free end of the 65 tongue is prolonged to interlock with the

opposite end flap c^2 . The latter instead of lying down on the box bottom as in the first described construction, is upturned and is embraced by two folds i i' of the prolonged part of the tongue B. This construction 70 avoids liability of the free end of the tongue becoming displaced in case no paste is used.

In the construction shown in Fig. 11 the tongue or false bottom extends only half 75 way through the box so as to form only one hump at one end, which will be quite sufficient to hold the article in many cases.

The box cover C shown in Fig. 12 and in section in Fig. 13, is made up in similar manner to the box or carton but has no inner tongue or false bottom, and preferably has side notches j j to facilitate the lifting off of the cover. The cover is made just large enough to slip over and closely embrace the exterior of the box. The parts lettered a b b' b^2 c and c' are precisely the same as the correspondingly lettered parts in Figs. 1 to 5. A tongue a' forms an inner lining. It is desirable to paste the inturned end flaps c' to the concealed end flaps b' and 90 also to paste the inturned side flaps b^2 to the sides b .

Figs. 14, 15 and 16 illustrate a construction in which the false bottom B is lifted above the bottom a of the box. The side 95 flaps b^2 are made wider than the previous constructions so as to form upturned flaps b^4 serving as supports for the false bottom. The latter may be formed as an end tongue in the manner shown in Fig. 2 or otherwise, 100 either integral with the main blank forming the box or as a separate piece. In either case it may be cut out to form an opening e^2 , Fig. 14, into which the article may partly enter, as shown by the dotted lines x in Fig. 16. 105 This construction dispenses with the humps shown in the previously described figures. Instead of cutting out an opening e^2 the tongue B may be embossed to form a depression, as shown in Fig. 16^a, where the embossed portion is lettered k . In this figure the upturned tongues b^4 are omitted, being superseded by downturned marginal flanges 110 l formed on the tongue or false bottom B.

The cartons thus far described are adapted for holding only one article. Fig. 17 shows a carton enlarged laterally so as to contain a multiplicity of articles. The construction is precisely the same as shown in Figs. 1 to 5, except that the box bottom 115 section a is made as many times wider as is desired, with a corresponding widening of the tongue B, forming the false bottom. The latter is shown slit at m m forming separate tongues which may be inserted 120 separately if desired. The humps g g are shown as continuous, this however not being essential. The box ends c c are so widened as to become in effect the sides of 125 the box.

- In the construction shown in Figs. 18, 19 and 20 the tongue or false bottom is formed as a prolongation of one of the side flaps b^2 , the portions $d d'$ forming the hump being separated from the side flap by slits $n n$. The box is folded together in the manner already described, except that the side flap b^2 to which the tongue section is joined is folded in last, the hump sections $d d'$ being first folded back so that the tongue is shortened sufficiently to enter within the length of the box, after which these sections are permitted to spring out to form the humps $g g$ Fig. 18, their ends entering into the opposite end corners of the box, and the middle section f being best fastened down with paste, although this is not necessary. The box has end flaps c^2 at both ends which may desirably be pasted down to the bottom.
- In Fig. 21 is shown a combined box and cover, the box being of precisely the same construction as shown in Fig. 3, while the cover differs from that shown in Fig. 12 in that it is formed with an inner tongue having humps g^2 constructed as a precise duplicate of the parts shown in Fig. 1, except for the preferred formation of the notches j , and except also that the humps g^2 are displaced inwardly from the ends, so that when the cover is applied they fit between the humps $g g$ of the box, as shown in dotted lines in the lower part of Fig. 21. With this construction the article shown by dotted lines x is confined between the humps of the box and cover, and held apart from the bottom and sides of the box and the corresponding parts of the cover.
- In Figs. 22 to 25 is shown a further modification the box proper being of the same construction already described, except that its false bottom B^3 is made as a flap prolonged from one of the side flaps b^2 and formed with holes $e e'$, and with longitudinal creases on which when bent into the box its middle sections $p p$ are bent down, as best shown in cross-section Fig. 23, while its end sections $q q$ stand up, so that they may serve to locate the positions of the ends of the article.
- The various modified constructions shown and described are given as illustrations, it

being obvious that the invention may be further modified without departing from its essential features as set forth in the claims.

55

I claim as my invention:—

1. A paper box formed of a single sheet, having flaps joined to form the sides and ends, and having an inner portion integral therewith partially filling the box and shaped to fit the article to be inclosed, having humped portions making edge contact with the side flaps whereby to hold the flaps in place.

2. A paper box having portions turned up and joined to form the sides and ends, and having an inner portion partially filling the box and formed integral with an end portion thereof, and having humps partly cut away to fit the article to be inclosed, said humps making edge contact with the sides of the box.

3. A paper box and a cover therefor each formed of a sheet having portions turned up and joined to form the sides and ends, and having inturned flaps and having an inner portion partially filling the space between such sides and ends and holding such flaps in place and bent up to form humps projecting within the box and cover respectively, the humps in the box and those in the cover relatively adapted to embrace between them an article to be inclosed.

4. A paper box and a cover therefor each formed of a sheet having portions turned up and joined to form the sides and ends, and having an inner portion partially filling the space between such sides and ends and bent up to form humps projecting within the box and cover respectively, the humps in the box and those in the cover being non-coincident, and being relatively adapted to embrace between them an article to be inclosed.

In witness whereof, I have hereunto signed my name in the presence of two subscribing witnesses.

EMIL EISENKRAFT.
